UNITED STATES PATENT OFFICE.

BENJAMIN LIPPER, OF PHILADELPHIA, PENNSYLVANIA, ASSIGNOR TO HIMSELF, AUGUSTUS A. LARZARUS, AND ISAAC A. SCHWARZ, OF SAME PLACE.

DESIGN FOR TRIMMING.

SPECIFICATION forming part of Design No. 16,499, dated February 2, 1836.

Application filed September 28, 1835. Serial No. 173,485. Term of patent 3½ years.

To all whom it may concern:

Be it known that I, BENJAMIN LIPPER, a citizen of the United States, residing in Philadelphia, Pennsylvania, have invented a new and original Design for Trimming for Garments, &c., of which the following is a specification.

My design is fully shown in the accompanying drawings, Figure 1 being a face view of a short strip of the trimming, and Fig. 2 a transverse section of the same.

The design is intended as an imitation of Astrakhan fur or feather trimming, the fabric *a* having a surface composed of threads forming loops *b*, small projecting rings or curls *d* being formed upon the threads of some or all

of the loops, so as to impart to the trimming a peculiar appearance not possessed by a trimming composed of plain looped threads.

I claim—

The design for trimming for garments, &c., said design consisting of a fabric having looped surface-threads with projecting rings or curls upon them, all substantially as specified and shown.

In testimony whereof I have signed my name to this specification in the presence of two subscribing witnesses.

BENJAMIN LIPPER.

Witnesses:

WILLIAM F. DAVIS,
HARRY SMITH.
